UNITED STATES PATENT OFFICE

2,113,627

SHOOK ALIGNING DEVICE

Albert I. Obermiller, Santa Ana, Calif., assignor to
 Food Machinery Corporation, San Jose, Calif.,
 a corporation of Delaware

Application December 28, 1936, Serial No. 117,710

3 Claims. (Cl. 1—14)

This invention relates to magazines from which slats or other similar elements are dispensed, the invention having particular utility in the nailing machine art.

5 In nailing machines of the automatic or semi-automatic type which are in general use for the manufacture of boxes, box parts such as the slats for forming the sides and bottom of the box are placed in the machine in the form of a stack from the bottom of which these slats are stripped one at a time as required by the machine. As the slats are placed in the magazine in small groups, the ends of the slats are generally out of alignment in such a way that there is a tendency for 10 the slats in the stack to bridge by binding against the downwardly converging end walls of the magazine. This bridging sometimes prevents the lowermost slat from being properly stripped from the magazine when its turn comes to be fed into position to be assembled in a box.

15 It is an object of this invention to eliminate the bridging aforementioned and thereby insure the timely stripping of slats from the lower end of the slat magazine as these are required. 20 Owing to the tendency of slats to bridge in a magazine where the end walls converge downwardly slat magazines have allowed such a degree 25 of end play by the slats contained therein that the ends of the slats are not aligned, when fed from the bottom end of the magazine, with the precise planes in which they must be located when assembled with the work. 30

35 It is another object of this invention, therefore, to not only prevent the bridging of slats in the slat magazine but to insure the location of the ends of each slat fed from the magazine in the precise planes in which said ends must lie when assembled with the work to which said slats are delivered.

40 The manner of accomplishing the foregoing objects, as well as further objects and advantages, will be made manifest in the following description taken in connection with the accompanying drawing, in which: 45 Fig. 1 is a fragmentary cross sectional diagrammatic view of a nailing machine of the type shown in U. S. Letters Patent No. 1,844,333 issued February 9, 1932 to E. C. Northrup on a Box machine, this figure illustrating a preferred embodiment of the present invention incorporated in said machine.

50 Fig. 2 is a fragmentary rear elevational view of Fig. 1 with the mechanism of the invention shown in retracted position. 55 Fig. 3 is a view similar to Fig. 2 and showing

the mechanism of the invention in slat aligning position.

In referring specifically to the drawing the old elements of the machine shown therein will be described only insofar as is necessary to show their cooperation with the specific structure embodying the present invention. Insofar as possible, however, reference to old elements of the machine will be made by use of the same reference characters with which these elements are identified in the aforesaid patent.

The nailing machine N includes a frame 2 and a nailing table 15 on which the work rests, this work including box ends 6 which are gripped by discs 17 so that the outer faces of the box ends 15 are disposed, while being worked upon, in a pair of precisely located vertical parallel planes. Mounted on the frame 2 over the work is a nailing cross head 31 which carries nail drivers 60 and nail carrying chucks 16, the cross head 31 reciprocating vertically so as to nail slats on three edges of the box ends 6 thereby forming a box. Nails driven from the chucks 16 in each nailing operation are driven approximately one-quarter of an inch inside of the outside planes 25 of the box ends 6.

Supported in a magazine M on the frame 2 is a stack of slats 10 which are adapted to be fed as required by a carriage 11 into position for nailing to the box ends 6. The carriage 11 is actuated by an arm 12 and carries box end feeding lugs 74 and slat feeding arms 86 upon which are provided hooks 87 which catch onto the lowermost slat in the stack 10 as the arms 86 move horizontally to the right underneath this stack and carry the slat 30 engaged into place over the box ends 6. As pointed out in said patent, suitable power mechanism is provided for coordinately actuating all of the elements mentioned hereinabove.

The stack 10 of slats includes a multiple of 40 series of slats each of which includes four side slats 10a, two of these being placed on each side of a pair of bottom slats 10b, the bottom slats, as shown in Fig. 1, being substantially wider than the side slats. The stack 10 rests upon a pair 45 of channel irons 130 just inside of which the arms 86 operate which strip the slats successively from the lower end of the stack 10.

The magazine M includes a back wall 131 and end walls 132 the latter converging downwardly 50 toward each other and being provided with cut-out recesses 133.

The magazine M is also provided with a slat aligning mechanism 135 which includes a pair of bearings 136 mounted on the magazine end 55

walls 132. These bearings rotatably support shafts 140 on the rear ends of which are fixed cam arms 141 and on the front ends of which are fixed lateral slat aligning arms 142. The 5 arms 141 are provided with cam faces 150 which are adapted to be engaged by rollers 151 mounted on posts 152 which extend horizontally from the nailing cross head 31 when this cross head descends to perform a nailing operation. The slat 10 aligning arms 142 are shaped inwardly as shown in Figs. 2 and 3 to have lower portions 160 inner faces of which are brought into coincidence with the same parallel vertical planes as those in which the outer faces of the box ends 6 lie 15 as above noted, this precise alignment taking place each time the rollers 151 move downwardly with the nailing cross head 31 so as to come into engagement with the cam faces 150 on the arms 141 as shown in Fig. 3.

20 When the cross head 31 is lifted so that the rollers 151 do not engage the cam faces 150 the arms 141 and 142 are held into the positions in which these are shown in Fig. 2 by contractile coil springs 162 connected to said arms which 25 are drawn by these springs into contact with adjustable stop screws 163 provided on the frame 2.

A comparison of Figs. 2 and 3 illustrates clearly how any bridging effect which might occur by endwise misalignment of successive slats or 30 groups of slats deposited in the stack 10 is progressively eliminated as these slats gravitate downwardly in the magazine M by the inner faces of the arm portions 160 being pressed inwardly to precisely coincide with the planes 35 bounding the opposite ends of the work onto which slats are to be assembled.

With the cause of bridging thus practically 40 eliminated the end walls 132 of the magazine M may be built to converge so that their inner faces at their lower ends also practically lie in the parallel vertical planes forming the end boundaries of the work. A feeding of the slats 10a and 10b into the precise positions necessary 45 for them to have in order to form a perfect box is thus assured.

What I claim is:

1. In a nailing machine, the combination of: means for supporting work with its opposite ends lying in two precisely located parallel planes;

magazine means for containing a stack of slats; means for stripping slats from the lower end of said stack in a direction at right angles with the longitudinal axis of said stack and parallel with said planes and carrying the slats so stripped so as to overlie said work; mechanism operating automatically and intermittently to press inwardly against the ends of a portion of the slats in said stack to adjust said slats as they gravitate downward to bring the opposite ends 10 of said slats into superimposed relation in the aforesaid parallel planes; and means for nailing said slat ends to said work when overlying the latter.

2. In a nailing machine the combination of: 15 means for supporting work with its opposite ends lying in two precisely located parallel planes; magazine means for containing a stack of slats with the ends of said slats approximately in said parallel planes; means for stripping 20 slats from the lower end of said stack in a direction parallel with said planes and carrying the slats so stripped so as to overlie said work; nailing mechanism disposed over said work and adapted to drive nails downwardly just within 25 said planes to nail said slats to said work; and means actuated by said nailing mechanism to intermittently press inwardly against the ends of a portion of the slats in said stack to adjust said slats as they gravitate downward to bring 30 the opposite ends of said slats into superimposed relation in the aforesaid parallel planes so that when said slats are stripped from the stack and carried into position overlying said work, the ends of said slats are in exact vertical alignment with 35 the ends of said work.

3. In combination: magazine means for containing a stack of slats or the like, said means including a pair of downwardly converging end 40 walls; means for stripping slats from the bottom of said stack in a direction at right angles to the longitudinal axis of said stack; and mechanism intermittently operative to press inward against the ends of at least a portion of the slats in said stack to adjust said slats thus pressed 45 against so that as they gravitate downwardly they will pass freely between the lower portions of the aforesaid magazine end walls.

ALBERT I. OBERMILLER.
